UNITED STATES PATENT OFFICE.

JAMES WHITCOMB, OF HILLSDALE, MICHIGAN, ASSIGNOR OF ONE-HALF TO C. F. KAPP, OF MANCHESTER, MICHIGAN.

SPEEDOMETER.

1,091,410.

Specification of Letters Patent. Patented Mar. 24, 1914.

Application filed May 15, 1913. Serial No. 767,939.

To all whom it may concern:

Be it known that I, JAMES WHITCOMB, a citizen of the United States of America, residing at Hillsdale, in the county of Hillsdale and State of Michigan, have invented new and useful Improvements in Speedometers, of which the following is a specification.

This invention relates to improvements in speedometers and has particular application to a combined speed indicator and register.

In carrying out the present invention, it is my purpose to provide a device of the class described which will be found especially useful on motor vehicles and the like and which will be driven from one of the ground wheels of the vehicle and whereby the speed or mileage per hour at which the vehicle is traveling, the number of miles the vehicle has traveled during the particular trip and the total number of miles that the vehicle has traveled since a predetermined time may be readily and conveniently ascertained.

It is also my purpose to provide a speedometer which will embody in its construction among other features a main shaft connected with one of the drive wheels of the vehicle and driven therefrom at a predetermined speed and in proportion to the diameter of the wheel, such shaft being connected up with the registering and indicating devices so as to actuate the latter in order that said devices will function properly and enable a correct reading to be ascertained at any time.

With the above and other objects in view, the invention consists in the construction, combination and arrangement of parts hereinafter set forth in and falling within the scope of the claims.

In the accompanying drawings: Figure 1 is a view in front elevation of a speedometer constructed in accordance with the present invention. Fig. 2 is a top plan view of the mechanism of the device, the cover of the casing being shown in section. Fig. 3 is a front elevation of the mechanism of the device, the cover of the casing being removed. Fig. 4 is a transverse sectional view on the line 4—4 of Fig. 2 looking in the direction of the arrow. Fig. 5 is a like view on the line 5—5 of Fig. 2 looking in the direction of the arrow. Fig. 6 is a fragmen-

tary sectional view through the trip register. Fig. 7 is a sectional view on the line 7—7 of Fig. 2 looking in the direction of the arrow.

The mechanism of my improved speedometer is inclosed in a casing comprising, in the present instance, a back plate 1 designed to be secured, in some appropriate manner, to the dash board of a motor vehicle and formed with a marginal flange 2, and a cover 3 having the edge thereof seated upon the flange 2, the cover and back plate being fastened together by any suitable means, or in any preferred manner.

Projecting outwardly from the back plate 1 and extending into the casing are brackets 4, 4 disposed in proximity to the opposite end of the back plate and carrying at their free extremities alining bearings in which is journaled a main shaft 5 having one end passed through an aperture in the cover 2 of the casing and connected up with one of the ground wheels of the vehicle.

The "total register" device comprises, in the present instance, four register wheels 6 having the peripheries thereof properly marked off and visible through a sight window 7 formed in the front wall of the casing. These register wheels are mounted upon a shaft 8 journaled in alining bearings carried by the free extremities of one of the end brackets 4 and a bracket 9 extending outwardly from the back plate and into the casing. The shaft 8 is preferably disposed in parallelism with the main shaft 5 and is driven from the latter shaft through a reducing gear system composed, in the present embodiment of my invention, of a worm 10 fixed to the main shaft and meshing with a worm wheel 11 keyed upon a stub shaft 12 journaled in alined bearings carried by a bracket 13 extending outwardly from the back plate and into the casing in a plane below the main shaft, the stub shaft being arranged at right angles to the main shaft. Fixed to the stub shaft is a worm 14 meshing with a worm wheel 15 surrounding the shaft 8 and equipped with a collar 16 disposed concentrically of the shaft and suitably connected with the first or units wheel 6. It will, of course, be understood that the register wheels 6 are connected to one another for progressive movement in any desired manner so that when the first or units wheel has made one complete revo-

lution the second or tens wheel will move through the required distance, the last wheel, in turn, imparting motion to the third or hundredths wheel at the proper time, and so on throughout the series of 5 wheels.

In the present instance, the "trip register" device comprises a single wheel 17 having the periphery thereof suitably marked off and visible through a sight window 18 formed in the front wall of the casing. This wheel 17 loosely surrounds the shaft 8 and has one face thereof contacting with the free face of the worm wheel 18 and held in engagement therewith through the medium of a coiled expansion spring 18 loosely surrounding the shaft 8 and having one end bearing upon the hub of the wheel 17 and the opposite end abutting a collar 19 surrounding 10 the shaft 8 and fast thereon by means of a set screw 20. In the form of my invention selected for illustrative purposes, the face of the worm wheel 18 in contact with the adjacent face of the register wheel 25 17 is formed with an annular row of depressions 21 suitably spaced apart and designed to receive a pin 22 carried by the confronting face of the register wheel.

The speed indicating device for showing 30 the speed, in miles per hour, at which the vehicle is moving, consists of a disk 23 suitably secured upon one end of a sleeve 24 rotatably mounted upon a stud 25 carried by the bearing on the free end of the bracket 9 35 and disposed in a plane above and at right angles to the adjacent end of the shaft 8. The front face of this disk 23 is suitably graduated or marked off and disposed in a plane parallel with the front wall of the casing, the graduations on the disk being visible 40 through a sight window 26 formed in the front wall of the casing. Fixed to the shaft 5 approximately centrally thereof is a collar 27 provided at diametrically opposite points 45 with outwardly projecting curved arms 28, 28, while bell crank levers 29, 29 are each pivoted at its bight to the free end of one of the arms 28, as at 30, such levers having the free extremities of the inner limbs thereof 50 disposed within a groove 31 formed in one end of a sleeve 32 loosely surrounding the main shaft in proximity to the collar 27. The free ends of the outer limbs of the bell 55 crank levers 29 carry balls 33 or other forms of weights which, in the rotation of the main shaft, tend to swing outwardly under the action of centrifugal force and so slide the sleeve 32 along the main shaft, a contractile spring 34 being connected to the outer limbs 60 of the bell crank levers to hold the latter at their limit of inward movement. Fulcrumed at one end between pivot ears 35 extending outwardly from the back plate 1 is a lever 36 terminating in proximity to the 65 front wall of the casing and pivotally con-

nected, as at 36, with one end of a rack bar 38 having the teeth thereof meshing with a pinion 39 fixed upon the inner end of the sleeve 24 carrying the disk 23. The free end of the sleeve 32 surrounding the main shaft 70 is pivotally connected as at 40 with the lever 36 so as to swing the latter about its fulcrum when the governor arms swing outwardly under the action of centrifugal force.

From the foregoing description taken in 75 connection with the accompanying drawings, the construction, mode of operation and manner of employing my invention will be readily apparent. In this instance, the speed of the main shaft 5 is intended to be 80 approximately five hundred revolutions for each mile of travel of the machine in which the speedometer is installed, although it depends entirely upon the size of the wheel, what the driving connection between the 85 shaft and wheel will be to produce this ratio, while the shaft 8 moves through one-tenth of a revolution to every five hundred revolutions of the main shaft. In other words; every mile of travel of the vehicle will cause 90 the shaft 8 to rotate through one hundred and thirty-six degrees. Thus, each revolution of the shaft 8 corresponds to one mile of travel. For this reason, the periphery of 95 each register disk is divided or graduated into ten equal parts each representing one mile of travel. As the main shaft 5 rotates incident to the travel of the vehicle, the levers 29, 29 swing about the pivot points 30 under the action of the weights 33, due to 100 centrifugal force, and so slide the sleeve 32 along the main shaft with the result that the disk 23 is rotated through the medium of the lever 36, rack bar 38 and pinion 39. The disk 23 rotates until the number thereon corresponding to the speed of the vehicle registers with an indicating mark in the window 26. Thus, the speed, in miles per hour, at 105 which the vehicle is moving may be readily determined. Motion is transmitted from the main shaft to the shaft 8 through the step down gear system hereinbefore described and the latter shaft makes one-tenth of a revolution to every five hundred revolutions of the main shaft. Thus, the disks of the "total 110 register" device are actuated successively in order that the total number of miles the vehicle has traveled during a predetermined period may be readily ascertained. The wheel of the "trip register" device being 115 fast to the worm wheel 18 on the shaft 8 and rotating with such worm wheel, enables the length of the particular trip to be determined. By sliding the wheel 17 along the shaft 8 against the action of the spring 18, 120 the pin 22 may be disengaged from the respective depression or recess 21 and the wheel rotated manually so that the "trip register" device may be reset.

While I have herein shown and described 125

one preferred form of my invention by way of illustration, I desire to have it understood that I do not limit or confine myself to the precise details of construction herein described and delineated, as modification and variation may be made within the scope of the claims without departing from the spirit of the invention.

I claim:

- 10 1. A speedometer comprising a main shaft adapted to be driven from a vehicle wheel, a speed indicating device comprising a disk, a collar fixed to said shaft, arms radiating from said collar at diametrically opposite points, bell crank levers each pivoted at its bight to one of said arms, a sleeve on said shaft and adapted for sliding movement thereon and having one end thereof formed with a groove designed to receive the free extremities of the inner limbs of said bell crank levers, weights carried by the free ends of the outer limbs of said levers and responsive to the action of centrifugal force to slide the sleeve along the shaft, a lever fulcrumed at one end, a rack bar pivoted to the free end of said lever, a pinion fixed to said disk and meshing with said rack bar, and a connection between said sleeve and lever whereby the disk will be rotated in the movement of the sleeve along the shaft and through an angle corresponding to the speed of the shaft.

15 2. A speedometer comprising a main shaft adapted to be driven from a vehicle wheel, a speed indicating device comprising a disk, a collar fixed to said shaft, a governor carried by said collar and responsive to the action of centrifugal force, a sleeve mounted on said shaft and capable of sliding movement thereon, a connection between said governor and sleeve, a lever fulcrumed at one end, a rack bar pivoted to the free end of said lever, a pinion fixed to said disk and meshing with said rack bar, and a connection between said sleeve and lever whereby the disk will be rotated in the movement of the sleeve along the shaft and through an angle corresponding to the speed of the shaft.

20 3. A speedometer comprising a main shaft adapted to be driven from a vehicle wheel, a speed indicating device comprising a disk, a collar fixed to said shaft, arms radiating from said collar at diametrically opposite points, bell crank levers each pivoted at its bight to one of said arms, a sleeve on said shaft and adapted for sliding movement thereon and having one end thereof formed with a groove designed to receive the free extremities of the inner limbs of said bell crank levers, weights carried by the free ends of the outer limbs of said levers and responsive to the action of centrifugal force to slide the sleeve along the shaft, a lever fulcrumed at one end, a rack bar pivoted to the free end of said lever, a pinion fixed to said disk and meshing with said rack bar, and a connection between said sleeve and lever whereby the disk will be rotated in the movement of the sleeve along the shaft and through an angle corresponding to the speed of the shaft.

25 4. A speedometer comprising a main shaft adapted to be driven from a vehicle wheel, a speed indicating device comprising a disk, a collar fixed to said shaft, arms radiating from said collar at diametrically opposite points, bell crank levers each pivoted at its bight to one of said arms, a sleeve on said shaft and adapted for sliding movement thereon and having one end thereof formed with a groove designed to receive the free extremities of the inner limbs of said bell crank levers, weights carried by the free ends of the outer limbs of said levers and responsive to the action of centrifugal force to slide the sleeve along the shaft, a lever fulcrumed at one end, a rack bar pivoted to the free end of said lever, a pinion fixed to said disk and meshing with said rack bar, and a connection between said sleeve and lever whereby the disk will be rotated in the movement of the sleeve along the shaft and through an angle corresponding to the speed of the shaft.

30 5. A speedometer comprising a main shaft adapted to be driven from a vehicle wheel, a speed indicating device comprising a disk, a collar fixed to said shaft, arms radiating from said collar at diametrically opposite points, bell crank levers each pivoted at its bight to one of said arms, a sleeve on said shaft and adapted for sliding movement thereon and having one end thereof formed with a groove designed to receive the free extremities of the inner limbs of said bell crank levers, weights carried by the free ends of the outer limbs of said levers and responsive to the action of centrifugal force to slide the sleeve along the shaft, a lever fulcrumed at one end, a rack bar pivoted to the free end of said lever, a pinion fixed to said disk and meshing with said rack bar, and a connection between said sleeve and lever whereby the disk will be rotated in the movement of the sleeve along the shaft and through an angle corresponding to the speed of the shaft.

35 6. A speedometer comprising a main shaft adapted to be driven from a vehicle wheel, a speed indicating device comprising a disk, a collar fixed to said shaft, arms radiating from said collar at diametrically opposite points, bell crank levers each pivoted at its bight to one of said arms, a sleeve on said shaft and adapted for sliding movement thereon and having one end thereof formed with a groove designed to receive the free extremities of the inner limbs of said bell crank levers, weights carried by the free ends of the outer limbs of said levers and responsive to the action of centrifugal force to slide the sleeve along the shaft, a lever fulcrumed at one end, a rack bar pivoted to the free end of said lever, a pinion fixed to said disk and meshing with said rack bar, and a connection between said sleeve and lever whereby the disk will be rotated in the movement of the sleeve along the shaft and through an angle corresponding to the speed of the shaft.
